UNITED STATES PATENT OFFICE.

ALFRED N. OLSEN, OF ROCK RAPIDS, IOWA, ASSIGNOR TO VICTOR PIN-SETTER COMPANY, OF ROCK RAPIDS, IOWA.

PIN-SETTING MECHANISM.

1,414,787.

Specification of Letters Patent. Patented May 2, 1922.

Application filed February 28, 1921. Serial No. 448,402.

To all whom it may concern:

Be it known that I, ALFRED N. OLSEN, a citizen of the United States, residing at Rock Rapids, in the county of Lyon and State of Iowa, have invented certain new and useful Improvements in Pin-Setting Mechanisms, of which the following is a specification.

This invention relates to improvements in devices for automatically setting bowling pins upon their spots on the floor of a bowling alley and has as its general object the provision of means adapted, in an elevated position, to receive the pins when promiscuously placed thereon, and operating automatically when lowered and again elevated or retracted, to dispose the pins in upright position upon the floor of the bowling alley and accurately center the same upon their respective spots, thus obviating the tedious and uncertain setting of the pins by hand.

Another object of the invention is to provide pin setting means so constructed that if one or more of the pins should remain standing on their spots after other pins have been knocked down, none of the latter pins will require to be placed within the pockets or units of the device, as, upon lowering of the device the empty pockets or units will accommodate themselves to the pins already standing, and in this connection the invention has as its further object to so construct the units of the device that should any pins be left standing and not accurately centered on their respective spots, lowering of the device, to set and spot the pins which have been knocked down and deposited in the proper units of the device, will result also in automatic repositioning of the first-mentioned pins so as to center the same upon their respective spots.

Another object of the invention is to so construct the device that it will be substantial and durable and not liable to have its parts disarranged or damaged when pins are carelessly thrown into the units thereof.

Another object of the invention is to provide a device for the purpose stated in which the pin-receiving units are received within a frame and in which means are provided for counter-balancing the frame in its up and down movement so that but little exertion is required to effect lowering of the

frame to set the pins upon their spots, and after this has been done the counter-balancing means will act automatically to elevate the frame until it has been brought clear of the pins.

Still another object of the invention is to so construct and arrange the frame and the units contained therein as to provide for depositing of the pins in the units with a maximum degree of convenience and without the necessity of exercising any special care.

In the accompanying drawings:

Figure 1 is a side elevation of the mechanism embodying the invention arranged within a bowling alley, the frame in which the pin-receiving units are arranged being shown lowered to a position adjacent the floor of the alley and having a number of pins placed therein for the purpose of being spotted upon the said floor;

Figure 2 is a similar view illustrating the frame fully lowered;

Figure 3 is a detail front to rear sectional view through one of the pin-receiving units, the bolstering member being shown in the position which it assumes by gravity when the unit is elevated and is in position to receive a pin;

Figure 4 is a similar view illustrating the unit lowered and the pin bolstering member shifted to position to release the pin;

Figure 5 is a similar view illustrating the unit partly elevated;

Figure 6 is a similar view illustrating the unit further elevated;

Figure 7 is a perspective view of the bolstering member looking at the forward side thereof;

Figure 8 is a similar view of the said member looking at the rear side thereof;

Figure 9 is a perspective view of a fixed abutment member which constitutes a part of the unit.

The mechanism embodying the present invention comprises an assemblage of ten pin receiving and setting units which are of counterpart construction and which are arranged within a triangular frame indicated in general by the numeral 1, this frame being arranged for vertical movement within the bowling alley 2 above the floor 3 thereof by any suitable guiding means indi-

cated by the numeral 4, the frame being counterbalanced by weights 5 connected with the ends of cables 6 which are led over pulleys 7 arranged above the alley and which 5 cables are connected, as at 8, to the opposite sides of the frame 1. The drawings illustrate only one weight and its respective cable and pulley but it will be understood that an assemblage of these elements is employed at each side of the alley and connected with each side of the frame 1.

Each unit of the mechanism comprises a box indicated in general by the numeral 9, these boxes being arranged in proper pyramidal order within the frame 1 and each 15 box comprising sides 10, a front wall 11, and a rear wall 12. The side walls 10 of each box are vertically disposed as is also the front wall 11, but the rear wall 12 is disposed in a plane inclined upwardly and rearwardly, as clearly shown in Figures 3, 4, 5 and 6 of the drawings.

Each unit further comprises an abutment member and a bolstering member which 25 members are mounted respectively within the rear and forward ends of the box 9 and therefore coact respectively with the rear and forward sides of a bowling pin disposed within the unit. The abutment member is indicated in general by the numeral 13 and the same comprises a body 14 having flat parallel sides 15 which seat beside the inner faces of the side walls 10 of the box, the body having an intermediate portion 30 which is transversely curved, as at 16, to conform substantially to the peripheral contour of the body of the ordinary pin. The lower portion of the body 14 is so formed that its inner or curved surface 16 is 35 of substantially semi-cylindrical contour but above this portion the body has its said surface of approximately inverted conical form and therefore receding in a rearward direction as indicated by the numeral 17, the uppermost portion of the body being inclined 40 forwardly or in an opposite direction as indicated by the numeral 18. At the juncture of the portions 17 and 18 the body is provided upon its rear side with a horizontal 45 flange 19 designed to rest upon the upper edge of the rear wall 11 of the box 9 and be secured thereto by screws or other suitable fastening elements 20. Likewise a bolt 21 may be passed through the lower 50 portion of the body 14 and through the said wall 11 so as to secure the member 13 rigidly in place within the rear end of the respective box. Due to the downward and inward inclination of the surface portion 55 17, and the opposite inclination of the portion 18, the butt end of a pin thrown into the unit and striking the abutment member, will be guided downwardly and inwardly and the pin will be caused to assume 60 an approximately upright position when it

comes to rest between the abutment member and the bolstering member which latter will now be described.

The bolstering member is most clearly shown in Figures 7 and 8 of the drawings 70 and indicated in general by the numeral 22, and the said member comprises a body 23 having laterally downwardly projecting lugs 24. The body at its rear side and above the upper ends of the lugs is formed with a 75 head 26 having a transversely concave face 27. At its under side the head is formed with spaced pairs of apertured ears 28 in which are mounted spindles 29 supporting anti-friction rollers 30 which may be of 80 any material suitable for the purpose and which rollers are disposed with their axes at an obtuse angle to each other so that the rollers may engage the forward side of a pin disposed within the unit at points at 85 opposite sides of the middle front of the pin. Preferably the spindles 29 are provided at their relatively remote ends with heads 31 which engage the outer faces of the uppermost ears 28, and the relatively 90 adjacent ends of the spindles project beyond the relatively adjacent ears 28 of the two pairs and are formed with openings 32 through which may be threaded a tying wire 33 which prevents displacement of the 95 spindles but which may be readily untied to permit of withdrawal of either spindle for the replacement of the respective roller 30 whenever this becomes necessary. The outer sides of the legs 24 constitute extensions of 100 the lateral edges of the body 23, and these portions of the member are slidably disposed within grooves 34 formed in the opposing faces of the side walls 10 of the box 9, the said grooves being inclined to correspond to the inclination of the rear wall 12 of the box and being located immediately rearwardly of the said wall. The head 26 is hollow in its rear side and within the recess thus provided are formed ears 35 supporting spindles 36 upon which are mounted anti-friction rollers 37, these rollers being 105 designed to ride against the rearwardly presented face of the front wall 12 of the unit in the up and down shifting movement of 110 the bolstering member. For a purpose to be presently explained the rear face of the rear wall 12 of the unit comprises upper and lower relatively offset portions 38 and 39 respectively and an intervening shoulder 40, 115 the portion 38 being spaced forwardly with relation to the plane of the portion 39, and the shoulder 40 merging with the said surface portions 38 and 39 in a manner to provide for free travel of the rollers 37 over 120 the said portions 38 and 39 and the shoulder portion 40. The body 23 of the bolstering member is provided at its upper side with a 125 rearwardly projecting flange 41 designed, in the full lowered and normal position of the 130

member, to rest upon the upper edge of the inclined rear wall 12 of the box so as to limit the downward movement of the member to the position shown in Figures 3 and 5 6 of the drawings.

When the frame of the mechanism is in elevated position to receive the pins to be set or spotted, the bolstering member 22 will occupy the lowered position shown in Figure 3 of the drawings and when the member is in this position the rollers 37 will rest against the surface 39 of the rear wall 12, and the rollers 30 will be spaced from the adjacent side of the abutment member 13 a 10 distance less than the maximum diameter of the body of the pin so that when a pin is dropped or thrown into the unit it will strike against the abutment member and be bolstered between this member and the said member 22, the forward side of the pin engaging the curved inner surface of the abutment member 13 and the rear side of the pin engaging the rollers 30. When the mechanism is lowered for the purpose of 15 spotting the pins, the lower ends of the legs 25 24 of the bolstering member will come in contact with the floor of the alley and this member will be bodily shifted in an upward and rearward direction, and as these rollers 30 37 ride upwardly over the surface 39 and onto the shouldered portion 40, the member will be guided so as to recede from the pin until it has assumed about the position shown in Figure 4 of the drawings in which 35 35 position of the parts the pin will be upright upon the floor of the alley. The grooves 34 are of sufficient width to permit of play of the bolstering member forwardly and rearwardly with relation to the rear wall 12, 40 and by reason of this play, the said bolstering member is permitted to move forwardly as well as upwardly when its rollers 37 pass from the surface 39 over the shoulder 40 and onto the surface 38. After the frame 45 has been lowered to the position shown in Figure 4 and is released, the counterbalancing weights associated therewith will immediately act to elevate the frame and as this movement takes place the rollers 37 50 50 will again ride onto the shoulder 40 as shown in Figure 5 of the drawings and finally onto the surface 39 as shown in Figure 6, the bolstering member bodily moving downwardly and rearwardly until it finally assumes the position shown in said Figure 6. 55 In the meantime however this member as well as the abutment member 13, has cleared the pin which is left standing in an upright position upon its spot. By providing the 60 shoulder 40 and the relatively offset or displaced surfaces 38 and 39 above and below the shoulder, the bolstering member is permitted to recede from the pin as the pin is released and caused to assume an upright 65 position upon the floor of the alley, and on

the other hand the said bolstering member is moved rearwardly as the unit is elevated clear of the pin, so as to automatically assume a position to bolster the pin next placed within the unit.

70

Having thus described the invention, what is claimed as new is:

1. In pin setting mechanism, a pin-receiving unit movable upwardly and downwardly and comprising spaced walls, an abutment 75 member carried by one of said walls, the other wall having an inclined surface and a shoulder at the upper portion of the surface, and a bolstering member disposed within the unit and having means riding in contact with the last-mentioned wall and adapted, in the lowered position of the bolstering member, to support the same by contact with the inclined surface of the wall and, in the upward movement of the bolstering member, to ride over the said shoulder and permit the member to recede from the pin engaged thereby, the said bolstering member having a floor-engaging part to influence such movement.

2. In pin setting mechanism, a pin-receiving unit comprising spaced walls, an upright abutment member upon one of said walls, the other wall having an inclined surface, the upper and lower portions of which 90 are relatively offset, and a bolstering member mounted within the unit and having means riding in engagement with the inclined surface of the last-mentioned wall, the bolstering member having a floor-engaging part to influence upward movement of the member when the unit is lowered.

3. In pin setting mechanism, a pin-receiving unit movable upwardly and downwardly and comprising a wall having an inclined 105 surface the upper and lower portions of which are relatively offset and connected by a shoulder, an abutment member disposed opposite the said wall, and a bolstering member mounted within the unit and normally assuming by gravity a lowered position and having a floor-engaging part to influence movement in an upward direction, the said bolstering member embodying an anti-friction element riding in engagement 110 with the inclined face of the wall.

4. In pin setting mechanism, a pin-receiving unit movable upwardly and downwardly and embodying a wall having an inclined surface the upper and lower portions of 120 which are relatively offset and connected by a shoulder, and abutment member located opposite the said wall, a bolstering member mounted within the unit in juxtaposition to the wall and adapted to assume by gravity a lowered position, means limiting the lowering movement of the said bolstering member, and an anti-friction element carried by the bolstering member and positioned, in the lowered position of the 125 130

member, to engage against the lower portion of the inclined surface of the wall and thus support the bolstering member in bolstering position and arranged, in the upward movement of the member, to ride over the shoulder and toward the upper portion of the inclined wall surface and thus permit the bolstering member to recede from the pin, the bolstering member having a floor-engaging part to influence its upward movement.

5. In pin setting mechanism, a pin-receiving unit movable upwardly and downwardly and embodying a wall having an inclined surface the upper and lower portions of which are relatively offset and connected by a shoulder, and an abutment member located opposite the said wall, a bolstering member mounted within the unit in juxtaposition to the wall and adapted to assume by gravity a lowered position, means limiting the lowering movement of the said bolstering member, an anti-friction element carried by the bolstering member and positioned, in the lowered position of the member, to engage against the lower portion of the inclined surface of the wall and thus support the bolstering member in bolstering position

and arranged, in the upward movement of the member, to ride over the shoulder and 30 toward the upper portion of the inclined wall surface and thus permit the bolstering member to recede from the pin, the bolstering member having a floor-engaging part to influence its upward movement, and 35 spaced anti-friction elements mounted upon the inner side of the bolstering member for coaction with the body of a pin disposed within the unit.

6. In pin setting mechanism, a pin-receiving unit movable upwardly and downwardly and comprising a bolstering member having a floor-engaging part to influence its upward movement upon downward movement of the unit, spaced pairs of ears upon the bolstering member, a spindle mounted in the ears of each pair, an anti-friction element rotatably mounted upon each spindle between the respective ears, the relatively remote ends of the spindle having heads and the 50 relatively adjacent ends being apertured, and a bonding element fitted through the apertures in the last-mentioned ends of the spindles and connecting the said spindles.

In testimony whereof I affix my signature. 55
ALFRED N. OLSEN. [L.S.]
